Molex Receptacle Assembly Speedstack Connector, Apr. 24, 2013, Lisle, Illinois, USA (8 Pages).

Primary Examiner — Angela J Lee*Assistant Examiner* — Shawn T Gingrich(74) *Attorney, Agent, or Firm* — Banner & Witcoff, Ltd.(57) **CLAIM**

The ornamental design for a connector, as shown and described.

DESCRIPTION

FIG. 1 is a front top perspective view of a connector showing my new design;

FIG. 2 is a bottom front perspective view thereof;

FIG. 3 is a front view thereof;

FIG. 4 is a rear view thereof;

FIG. 5 is a top view thereof;

FIG. 6 is a bottom view thereof;

FIG. 7 is a right side view thereof; and,

FIG. 8 is a left side view thereof.

The broken lines depicting the remainder of the connector show features that form no part of the claimed design.

1 Claim, 8 Drawing Sheets(56)
